UNITED STATES PATENT OFFICE.

DAVID HOKE, OF ALTOONA, ASSIGNOR OF ONE-HALF TO HENRY ELIAS HOKE, OF CHAMBERSBURG, PENNSYLVANIA.

LOCKING DEVICE FOR SLIDING DOORS.

SPECIFICATION forming part of Letters Patent No. 311,760, dated February 3, 1885.

Application filed June 24, 1884. (No model.)

To all whom it may concern.

Be it known that I, DAVID HOKE, a citizen of the United States, residing at Altoona, in the county of Blair and State of Pennsylvania, 5 have invented certain new and useful Improvements in Locking Devices for Sliding Doors; and I do hereby declare the following to be a full, clear, and exact description of the invention, reference being had to the accompanying 10 drawings, which form part of this specification, in which—

Figure 1 is a side elevation of a car and its door with my improvement applied thereto. Fig. 2 is a longitudinal horizontal section of 15 car-side door and barring or locking device, showing door closed. Fig. 3 is a detail of a modification. Fig. 4 is a longitudinal section, showing door opened.

My invention has for its object to provide 20 for the sliding doors of freight or other cars a locking device which shall effectually and firmly hold the door in position and prevent destructive jarring and jolting, as hereinafter set forth.

25 My invention consists in the peculiar construction and combination of parts hereinafter fully set forth, having reference, principally, first, to a locking or barring lever having a hinge-connection with the door and operating 30 to bar the latter endwise; second, to the combination, with the locking or barring lever, of an abutment or socket in the side of the car, with which an enlarged head or end of the locking or barring lever engages; third, to the 35 combination, with the locking or barring lever having a mortise in its end, of a link attached to the side of the car and adapted and designed to enter said mortise when the door is closed, and to lie down in a recess in the side of the 40 car when the door is opened.

Referring to the accompanying drawings, A represent the side of a freight, stock, express, or other car, having an opening, B, designed to be closed by a door, C, which is adapted to 45 slide to and fro in guides or ways a a.

D represents a metallic bar or strap secured to the door C by bolts d d, and having a hinge connection or joint, E, by means of which there is secured to it a lever, F, which should be 50 made of wrought-iron. This lever terminates

at its hinge end in a head, F', of such width or depth horizontally that when closed, as hereinafter specified, its outer surface is flush with the outer surface of the bar D, while its lower or inner surface is inside the exterior plane of 55 the car-side A. Said head F' has a straight shoulder or end, f, and on its under side is beveled to form another shoulder, f'.

G represents an abutment or socket, consisting of a cast-metal box fitted in a recess, H, in 60 the car-side A, and firmly secured therein by bolts h h. One end of the socket is beveled, as shown at g, and the other end, g', is straight and in alignment with the end f of lever-head F', and with the edge c of the door C when the latter is closed.

I represents a link secured to an eyebolt, K, or staple in the car-side A, and L is a recess in said car-side A, in which said link can rest 70 inside of the exterior plane of the car-side when the door C is opened.

M is a mortise in the end of the lever G, adapted to receive the link I, a padlock, N, or equivalent fastening or bolt, being inserted in the link after its passage through said mortise. 75

The operation of the device is as follows: The door is first moved forward or slid along on its ways or guides until it closes the opening B. The lever F is then thrown backwardly or inwardly toward the car-side until it meets 80 the latter, the link I passing through the mortise M, and being secured by a padlock or equivalent fastening. In moving back the lever the inner part of the head F' of said lever enters the socket G, its shoulder f' bearing 85 against the beveled end g of said socket, and its shoulder f abutting against the other end, g', of said socket, and also against the edge c of the door C and the end d' of the strap or bar D. This movement of the lever accordingly 90 tends to move the door forward if the latter be not already closed, and when the complete closure of the door is effected the lever serves to dog or bar it against endwise movement, securing said door most firmly in a closed position, and effectually preventing its jarring loose or being opened until the lever is released. If the parts be accurately fitted, there will be no strain of any moment on the hinge E when the door is secured, whatever strain 95 100

there is being exerted lengthwise of the lever or bar F.

The locking device herein described may be used for sliding doors other than those on cars, 5 and the part A in the drawings, representing a car-side, may also stand for the wall of a building having a sliding door.

If it be desired to secure the door in a partly opened condition, this may be effected by the 10 provision of a second abutment or socket at the required distance back of the socket G and a second link back of the link I.

If it be desired to draw the door by the action of the lever laterally toward the car-side 15 A and to hold it firmly against said side, this may be accomplished by forming the lever F with a projecting beveled toe, f², the end of the socket G having a correspondingly-beveled under-cut, g², to which said toe enters, as 20 shown in Fig. 3 of the drawings.

What I claim as my invention is as follows:

1. In a locking device for sliding doors of cars, the combination, with the door, of a strap secured thereto, a lever hinged to said strap 25 and having a head upon its inner side, and a socket or shoulder attached to the side of the car in such position that the head on the lever will engage therewith when the door is closed and the lever swung around against the car- 30 side, substantially as described, whereby the door is secured against endwise movement.

2. In a locking device for sliding doors of

cars, the combination, with the door C and the socket G in the car-side, of the strap D, secured to the outside of the door, the lever F, having 35 a head, F', one of whose ends is inclined, as shown, and the said head being adapted to enter the said socket when the lever is swung around, the inclined end bearing against one end of the socket and forcing the door against 40 its jamb, substantially as described.

3. The combination, with side or wall A and sliding door C, of strap or bar D, hinge E, lever F, having enlarged head F', socket or abutment G, link I, and bolt K, pivotally securing 45 the said link to the side of the car, said several parts being constructed and combined for operation substantially as shown and described, and for the purpose set forth.

4. The combination, with the sliding door C, 50 having a locking lever or bar, F, of a link, I, jointed in a recess in the side A, whereby said link may be brought into engagement with said lever or bar when the door is closed, and will lie down in said recess behind said door when 55 the latter is open, substantially as shown and described.

In testimony that I claim the foregoing I have hereunto set my hand this 19th day of June, 1884.

DAVID HOKE.
